UNITED STATES PATENT OFFICE

BENSON R. SHAW, OF ST. LOUIS, MISSOURI, AND FRANK BUCHANAN, OF SYRACUSE, NEW YORK, ASSIGNORS TO CROUSE-HINDS COMPANY, OF SYRACUSE, NEW YORK, A CORPORATION OF NEW YORK

BOUNDARY LIGHT FOR AIRPORTS AND THE LIKE

Application filed September 11, 1929. Serial No. 391,886.

This invention has for its object, a lamp for air ports and other fields, which is demountable when struck as by an airplane and which can be demounted without injury and 5 immediately be replaced without loss of time. In other words, it has for its object, a lamp which can be knocked over without being injured and immediately replaced.

It further has for its object a particularly 10 simple and efficient means, whereby when it is demounted, the electric feed circuit is not broken to other lamps normally connected in circuit with the demounted lamp. It further has for its object, a demountable lamp 15 structure which is particularly simple and durable in construction and highly efficient in use.

The invention consists in the novel features and in the combinations and constructions 20 hereinafter set forth and claimed.

In describing this invention, reference is had to the accompanying drawings in which like characters designate corresponding parts in all the views.

25 Figure 1 is an elevation, partly broken away, of this lamp, the contiguous portion of the earth base and of the service conduits being also shown.

Figure 2 is an enlarged, perspective view 30 of the base of the lamp.

Figure 3 is an enlarged, vertical, sectional view of this lamp.

This lamp comprises, generally, a base permanently mountable upon an earth, concrete, 35 asphalt or similar formed foundation, a demountable superstructure mounted on the base, the base and the superstructure being detachably interlocked or frictionally interlocked, as by snap catches, so that when the 40 superstructure is struck by sufficient force to overturn it, the superstructure will demount from the base. The base and the superstructure are also provided with normally engaged contacts which separate when the superstruc- 45 ture is demounted.

It further comprises a normally open cover which automatically closes to cover the portion of the base on which the contacts are mounted when the superstructure is over- 50 turned.

1 designates the base which is shown as discoidal in general form and provided with an outer upright annular face 2 having an outwardly extending annular lip or shoulder 3. The base is also provided with a central chamber 4 having openings 5 for receiving the conduit 6 enclosing the service wires. The chamber 4 has an upwardly extending annular wall 7 extending above the face of the base. 55

8 is a block of insulation suitably supported in the chamber 4 and having two pairs of opposing contacts 9 which engage each other when the superstructure is demounted, but which are separated by contacts 10 to be presently described, when the superstructure is mounted on the base. 60

The superstructure comprises a pedestal 11, a lamp designated generally 12 mounted on the upper end of the pedestal and devices such as wings or vanes 13 projecting from the pedestal beneath the lamp, these being colored or striped so as to be easily visible, or so as to aid the aviator to determine the location of the lamp. The pedestal 11 is tubular and preferably tapered from its lower end toward its upper end and the lower margin thereof surrounds the upright face 2 of the base and the pedestal rests at its lower edge on the flange 3 of the base. The base and the pedestal are provided with interlocking means which will unlock when sufficient force is applied to the superstructure to overturn it. The locking means is strong enough to resist the force of ordinary winds against the vanes. 75 80 85

In the illustrated embodiment of our invention, the base is provided with a plurality of friction latches 14, these being flat springs secured to the top of the base and extending downwardly into recesses 15 90 formed in the base. The latches 14 are provided with rounding engaging ends at 16 which snap into an internal annular groove 17 at the lower end of the pedestal. A support 18 from which is suspended a flexible electric cable 19 is provided in the pedestal near its upper end thereof. The cable 19 is secured in the support by a wedge W and screw S, the wedge and the support having faces arranged to coact inclined plane fash- 95 100

ion when the screw is tightened, the screw threading into the support and extending through an enlarged hole or slot in the wedge.

20 is a chamber mounted on the lower end of the cable 19 and forming a cover for the chamber 4, the chamber 20 being bell-shaped and having a shoulder 21 which coacts with the upper edge of the flange 7 of the chamber 4 and with a skirt 22 which encircles the flange 7 and preferably, meets at its edge the upper face of the base 1. It is secured to the lower end of the suspended cable 19 by a packing 23 around the lower end of the cable and within the neck 24 of the bell-shaped chamber 20 and a nut threading on the neck 24. The packing is resilient and forms an air tight joint around the cable 19 and prevents air from either entering or leaving the chamber 20 at this joint. The lower portion of the base where the electric wires from the conduits 6 enter, is filled with a suitable sealing and insulating compound such as pitch or the like. This prevents air from entering or leaving the chamber 4 through the conduit openings. The long skirt 22 previously referred to forms a fairly close fit with the flange 7, but does not form an air tight joint. With this construction, it can be readily seen that should water rise on the field to a level higher than the top of the flange 7, it can not enter the chambers inasmuch as they are filled with air and all outlets are sealed.

25 is a support of insulation for the terminals 10 previously referred to.

26 are wires leading from binding posts 27 on the support 25 to the lamp terminals, not shown, the wires extending through the cable 19.

28 is a normally open, spring-pressed cover for the chamber 4, this cover being hinged to the top of the base at 29 and arranged to be held open by the bell-shaped chamber 20 and to swing into closed position under the influence of the spring 30 to cover the chamber 4 when the superstructure is demounted.

The vanes 13 project radially from a wide collar 31 mounted on the upper end of the pedestal 2, the collar having laterally extending lugs 32 to which the vanes are bolted. A portion of the collar encircles the portion of the pedestal in which the cable support 18 is mounted and the collar and support are secured to the pedestal by screws S² extending through the walls of the collars and the pedestal and a conical flange of the support 18 which flange fits the pedestal. This collar is also provided with a base 33 for the lamp 12. The lamp is covered with a suitable globe and cage and also may be provided with a shade 34 carried by the cage 35.

This lamp is designed to be used as a boundary light for airports and a number of them are arranged at suitable intervals around the boundary of the air field.

When the superstructure is struck, as by

an airplane, it will demount owing to the snap catches 14 and owing to the cable 19 and bell-shaped chamber 20, the terminals 10 in said chamber will separate from the terminals 9 in the chamber 4 of the base and immediately upon the demounting of the superstructure, the cover 28 will close and cover the chamber 4 and protect the contents thereof. Also, when the superstructure demounts, the contacts 9 will move into engagement with each other so the feed circuit through the other lamps connected in circuit, will not remain broken.

In the event that the lamp has been overturned, it can be readily replaced in working condition on the base as follows: The superstructure or pedestal 11 is placed over the base and pushed into position by compressing the snap springs into engagement with the annular groove 17 at the lower end of the pedestal. The hand hole cover 36 is then lifted and the hand inserted, lifting first the cover 28 and then inserting the plug housing 20 over the flange 7 of the base and pushing the same down thereby engaging the contacts 9 with the contacts 10.

In general practice, these lamps are installed in series, in which case, there is one wire running around the field entering at each light through one of the conduits 6 connected to the terminals 9 and passing out through the other conduit 6. These lights may however be used in a multiple or parallel installation, in which case, there would be two wires coming into and out of the base.

In the case of the series installation, it will be noted that the contacts 10 disengage from the contacts 9 before the skirt 22 is raised beyond the flange 7. This construction causes any arc that may be formed by the disengagement of these contacts to take place while the chambers are still closed. This feature is desirable to prevent ignition or explosion in case gasoline or the like from the airplane should be nearer the boundary light 110 when the same is struck and tipped over. It will be further noted that immediately upon withdrawal of the chamber 20 from the chamber 4, that the cover 28 closes the opening in the chamber 4 and thus protects persons and property from shock or damage by fire.

In the case of a multiple installation, it will be apparent to those skilled in the art, that different forms of contacts would necessarily be used so that upon the withdrawal of the chamber 20 and its supported contacts, the contacts on the insulated support 8 would not come in contact. It will also be noted that the portion of the lamp which is demounted carries no current whatsoever and the underground wire is not disturbed.

What we claim is:

1. A lamp of the class described comprising a base mountable upon the ground, a

hollow demountable post mounted on the base, the base having a central box portion having a wall projecting into the post, contacts in the box portion for connection to service wires, the post having a depending cable therein for connection to the lamp, contacts at the lower end of the cable for detachably engaging the former contacts, a housing carried at the lower end of the cable and coacting with the inwardly projecting portion of the box to cover the same and enclose the contacts.

2. A lamp of the class described comprising a base mountable upon the ground, a hollow demountable post mounted on the base, the base having a central box portion having a wall projecting into the post, contacts in the box portion for connection to service wires, the post having a depending cable therein for connection to the lamp, contacts at the lower end of the cable for detachably engaging the former contacts, a housing carrier at the lower end of the cable and coacting with the inwardly projecting portion of the box to cover the same and enclose the contacts, and a cover for the box portion, the cover being carried by the base within the hollow post and normally engaging the housing and held from closing movement thereby and being movable into closed position when the post and parts carried thereby are demounted.

In testimony whereof, we have hereunto signed our names at St. Louis, in the State of Missouri, this 31st day of August, 1929 and at Syracuse, in the county of Onondaga, and State of New York, this 28th day of August, 1929.
